UNITED STATES PATENT OFFICE

167,708

COMBINATION TELEPHONE STAND AND MEMORANDUM HOLDER

Alonzo Moore, Baltimore, Md.

Application February 21, 1952, Serial No. 18,625

Term of patent 7 years

(Cl. D26—14)

To all whom it may concern:

Be it known that I, Alonzo Moore, a citizen of the United States, residing at Baltimore, State of Maryland, have invented new, original, and ornamental Design for Combination Telephone Stand and Memorandum Holder, of which the following is a specification, reference being had to the accompanying drawing, forming a part hereof.

Fig. 1 is a top plan view of the combination telephone stand and memorandum holder.

Fig. 2 is a front elevation thereof, the telephone being illustrated in dotted lines.

Fig. 3 is a perspective view of my invention.

Fig. 4 is a side elevation, showing the slidable memorandum holder in its extended position, and

Fig. 5 is a bottom plan view.

The telephone shown in dotted lines in Fig. 2 is for illustrative purposes only.

I claim:

The ornamental design for a combination telephone stand and memorandum holder, as shown and described.

ALONZO MOORE.
